UNITED STATES PATENT OFFICE

EARL KENDALL, OF MELROSE PARK, ILLINOIS, ASSIGNOR OF ONE-HALF TO IRA E. COLE, OF MELROSE PARK, ILLINOIS

WHEEL PULLER

Application filed March 26, 1930. Serial No. 439,042.

The invention relates to improvements in wheel pullers and particularly to a readily adjustable pneumatic device for removing wheels, or the like, from their mountings.

5 An object of the invention is to provide an improved wheel puller, of the character referred to, that is universally adjustable.

Another object is to provide an improved pneumatic wheel puller, with improved means 10 for engaging a wheel and wheel mounting, that will not injure the threads on the wheel hub or the mounting axle, or injure the tire.

Another object is to provide a portable, light, pneumatic wheel puller, rapid and positive in operation, and highly efficient in 15 service.

Another object is to provide an improved device of the character referred to which may be inexpensively manufactured and readily 20 operatively associated with a wheel.

The foregoing and such other objects of the invention as will appear hereinafter as the description proceeds, will be more readily understood from a perusal of the following 25 specification, reference being had to the accompanying drawing, in which:

Fig. 1 is a perspective view of the improved pneumatic wheel puller, a wheel being shown in dotted outline.

30 Fig. 2 is a vertical longitudinal sectional view through the barrel of the improved device.

Fig. 3 is a fragmentary plan view of one end of the barrel.

35 Fig. 4 is a transverse sectional view taken on line 4—4 of Fig. 1.

Fig. 5 is an enlarged vertical sectional view through the operating valve.

40 Fig. 6 is a sectional view, with parts shown in elevation, taken substantially on line 6—6 of Fig. 1.

The improved pneumatic wheel puller includes adjustably mounted means for engaging over the end of the wheel mounting or 45 axle, having removable and adjustable wheel engaging arms and hook members extending therefrom. The improved device is entirely free of the wheel and mounting, and may readily be adjusted to any wheel size.

50 The improved wheel puller preferably in-

cludes a barrel 11 fixedly secured upon an adjustable bracket 12 for axial alignment with the wheel mounting or axle 13. The member 14 of mounting bracket 12 preferably carries a bracket 15 on its upper end secured, adjacent each end to the barrel 11, by suitable screws 16. Bracket 15 extends longitudinally along the barrel 11 and is spaced therefrom by bosses 17 for a purpose to be described later.

60 A suitable nose 18 is mounted on the open end of the barrel 11, and portion 19 of reduced diameter, on said nose extends into the end of the barrel and is secured therein by screws 16 and 21. The nose 18 preferably is 65 tapered outwardly, as shown, and a cut-out portion 22 is provided on its upper side to permit viewing of the wheel mounting 13 when the latter extends therein. The other end of the barrel 11 is closed by a suitable 70 plug or head 23 which may be sweated therein and secured by dowel pins 24 to insure a secure and air tight fit.

75 A plunger or piston 25 having a reduced diameter, as at 26, is mounted for reciprocation in the barrel 11, and a rod 27 extends rearwardly therefrom through the head 23. The rod 27 preferably is detachably secured to the plunger 25 by a ball and socket connection 28 and a suitable handle or knob 29 is provided on its outer end. The handle 29 and rod 27 provide means for manually moving the plunger 25 towards the closed or rear end of the barrel 11 prior to operating the 80 device.

85 As shown in Figs. 1 and 4, a saddle or yoke 31 is detachably mounted on the barrel 11, adjacent the nose 18. A rib or tapered flange 32 is formed on the inner surface of 90 the yoke 31, adjacent one edge, for engaging in one of a plurality of spaced circumferentially arranged notches or grooves 33 in the barrel 11. Extending downwardly from said yoke, on each side of the barrel 11, are parallel lugs 34, and a pin 35 extends through each of said lugs, below the barrel 11, to retain the yoke in place. As shown in Fig. 2, the pin 35 extends between the barrel and the mounting bracket 15, hence the yoke 31 along 95 100

the barrel 11 may readily be adjusted without removing pin 35.

Extending at right angles from the barrel 11 and on either side thereof are aligned arms 36, mounted in sockets 37 provided one on each side of the yoke 31. The socket engaging end of each arm 36 is provided with a plurality of holes 38 and a cotter pin 39, or the like, adjustably secures said arm in place.

10 Brackets 41 are removably and adjustably secured to arms 36, one adjacent the outer end of each arm. The bracket includes a sleeve-like portion 42 for receiving a hook member 43 preferably formed of square stock.

15 The hook member 43 is also slidably mounted within the bracket 41, adjustment thereof being effected by a suitable wing nut 44 mounted upon the threaded end 45 of the hook. In operation, the nose 18 of the barrel 11 is placed over the end of the axle 13 and the hooks 43 are engaged behind the tire, as shown in Fig. 6, fluid under pressure is admitted into the barrel 11 by manipulating valve 47 in the fluid inlet line 48.

20 The valve 47 preferably includes a body portion 49 having the usual valve seat 51 therein. A valve stem 52 having a tapered valve member 53 for engaging the valve seat 51 is mounted within the body 49. One end of the valve stem 52 is recessed to receive a spring 54; a depressed portion 55 in the body 49 forms a suitable guide for the recessed end of the valve stem. The spring 54 and the fluid under pressure in the line 48 maintain the valve 47 closed, preventing said fluid entering the barrel 11.

25 The other end of the valve stem 52 extends through a boss in the body 49 and an operating handle 56 formed with a sleeve portion 57 is mounted thereon. The flange on the plug 58, carried on the end of the valve stem 52, retains the handle in place. The stem 52 also is provided with a central longitudinal bore 59 extending inwardly from the upper end thereof and a port 61 provides communication between the interior of the valve and the bore 59. Another port 62, adjacent the upper end of the valve stem, communicates with the atmosphere.

30 The handle 56 is normally held outwardly of the upper end of the valve stem 52 by a compression spring 63. Operation of the wheel puller is effected upon depressing the handle 56. Initial depression moves the handle downwardly along the valve stem 52 whereupon the sleeve portion 57 closes port 62. Continued depression opens the valve at 51 and fluid under pressure is admitted into the barrel 11, behind plunger 25, through

35 passage 64. This fluid throws the plunger 25 violently against the end of axle 13 and the impact urges the wheel puller rearwardly, thus pulling the wheel 46 free of the axle 13.

40 Immediately upon release of the handle 56, said handle returns to normal position

thus opening the port 62, and the valve stem 52 moves upwardly to close the valve. The fluid within the barrel 11 is then free to escape through ports 61, bore 59, and port 62.

45 It can readily be understood that the instantaneous and positive action of the plunger 25, striking the end of the axle 13, must effect removal of the wheel. The improved device is rigidly constructed of a minimum 70 number of movable parts, thus providing a structure capable of withstanding continuous rough usage without becoming unserviceable.

50 Although an exemplary form of the improved device is described in the foregoing and illustrated in the accompanying drawing, it is to be understood that the improved pneumatic wheel puller may embody various modifications in structural detail without departing from the spirit of the invention or the scope of the appended claims.

55 I claim:

1. A wheel pulling device of the character described comprising, in combination, a vertically adjustable support, a horizontally disposed barrel on said support adapted to be arranged in axial alignment with a wheel mounting, one end of said barrel being open to receive the end of said mounting 60 and a closure on the other end, a fluid pressure operated reciprocable plunger in said barrel having means extending through said closure for moving said plunger toward the closed end of the barrel, a yoke mounted for adjustment longitudinally of said barrel, opposed horizontally disposed sockets in said yoke, an arm adjustable longitudinally in each socket, and a bracket one adjustable longitudinally on each arm, a socket in each bracket at right angles to said arms, a wheel engaging member adjustably mounted in each bracket, and means admitting fluid into said barrel to drive said plunger against said wheel mounting to urge the wheel therefrom. 100

2. A wheel pulling device of the character described comprising, in combination, a vertically adjustable support, a barrel mounted on said support adapted to be arranged in axial alignment with a wheel mounting, a yoke mounted for adjustment on said barrel having diametrically opposed sockets extending substantially horizontally therefrom, an arm mounted for adjustment in each of said sockets, a bracket adjustable along each arm, a socket in each of said brackets, wheel engaging members adjustably mounted in said sockets, a fluid actuated plunger in said barrel operable to strike the end of said wheel mounting to urge the wheel therefrom, and means extending beyond the end of said barrel to return said plunger to starting position. 110

3. A wheel pulling device of the character described comprising, in combination, a sup- 115

port, a barrel open at one end mounted on said support and adapted to be arranged in axial alignment with a wheel mounting, said barrel having its open end surrounding the 5 end of said mounting and being cut-away in part at said open end to permit viewing of said wheel mounting, a clamp mounted for adjustment on said barrel having diametrically opposed horizontal sockets thereon, an 10 arm removably mounted in each of said sockets, a bracket adjustable along each arm, a socket in each of said brackets, wheel engaging means adjustable in each of said last named sockets, and a fluid pressure actuated 15 plunger in said barrel adapted to strike the end of said mounting to urge the wheel therefrom.

In testimony whereof I affix my signature
at 10 South La Salle Street, Chicago, Illi-
nois.

EARL KENDALL.
